[57] CLAIM

The ornamental design for a rotating rear view truck and bus mirror, as shown and described.

DESCRIPTION

FIG. 1 is a top right, front perspective view of a rotating rear view truck and bus mirror showing my new design it being understood that the broke lines are for illustrative purposes only and form no part of the desired design;

FIG. 2 is a front elevational view thereof;

FIG. 3 is a right side elevational view thereof;

FIG. 4 is a top plan view thereof;

FIG. 5 is a rear elevational view thereof;

FIG. 6 is a left side elevational view thereof;

FIG. 7 is a bottom plan view thereof; and

FIG. 8 is a top, right, front perspective view of a rotating rear view truck and bus mirror showing a second embodiment of my new design the sole difference being that the bottom mirror is positioned under the lower right end of the top mirror as opposed to the lower left end of the top mirror as in the first embodiment thereof.
